UNITED STATES PATENT OFFICE.

JOHN A. SHANLEY, OF WORTHING, SOUTH DAKOTA.

WELL-DRILLING MACHINE.

1,196,594.

Specification of Letters Patent. Patented Aug. 29, 1916.

Application filed January 29, 1916. Serial No. 75,075.

To all whom it may concern:

Be it known that I, JOHN A. SHANLEY, a citizen of the United States, residing at Worthing, in the county of Lincoln and 5 State of South Dakota, have invented new and useful Improvements in Well-Drilling Machines, of which the following is a specification.

This invention is an improved well drilling machine.

The object of the invention is to provide an improved machine of this character which is extremely cheap and simple in construction; which requires only one man to 15 operate it; which enables the strokes of the drill tool to be regulated at will, and which enables the tool to be rapidly drawn up at any time required to prevent it from being caught by a cave in and which provides only 20 one drum which is used both for drilling and for drawing up the tool.

The invention consists in the construction, combination, and arrangement of devices, hereinafter described and claimed.

25 In the accompanying drawings:—Figure 1 is a side elevation of a well drilling machine constructed in accordance with my invention. Fig. 2 is a plan of the same partly in horizontal section on the plane indicated 30 by the line 2—2 of Fig. 1. Fig. 3 is partly an elevation and partly a sectional view on the plane indicated by the line 3—3 of Fig. 2.

A frame 1 is here shown which may in 35 practice be of any suitable size and construction and which may, if desired, be mounted on trucks, to facilitate the transportation of the machine from place to place. A pair of standards 2 rise from opposite sides 40 of the frame. A bar 3 connects the upper ends of the standards and is provided with a pulley 4. Braces 5 are provided for the standards as shown.

A shaft 6 is mounted in bearings 7 and is 45 provided at one end with a power pulley 8 which is driven by a power belt 9 to cause the shaft to revolve when the machine is to be operated. A spur wheel 10, to drive a fly wheel or balance wheel is fixed to the 50 shaft for rotation therewith. A cam 11 is arranged at one side of the spur wheel and is mounted on the shaft so that said cam can be turned independently of the shaft and the cam is provided with a peripheral cam 55 groove 12 which is provided at one side with an oblique or V-shaped portion 13. The

cam has a radial lever arm 14 which is connected by a link 15 with a lever 16. The lever may be employed for shifting the cam and may be secured at any desired position, 60 to hold the cam in adjusted position by a segment 17 and a dog 18.

A pair of tappet pins 19 operate in transverse openings in the spur wheel 10 and are arranged directly opposite each other and 65 on opposite sides of the shaft 6. Each tappet pin has an inwardly extending tappet stud or roller 20 which engages the cam groove 12. The length of the tappet pins is such that when their tappet studs are in the 70 straight portion of the cam groove, their outer ends project beyond one side of the spur wheel and when their tappet studs are in the apex of the oblique portion 13 of the cam groove, their outer ends are flush with 75 the corresponding side of the spur wheel.

A trip lever 21 for operating the rope 22 by which the tool 23 is suspended and raised and lowered, is pivotally mounted on the shaft and is arranged in the path of the 80 tappet pins. Said trip lever has a pulley 24 which is engaged by the rope. The rope also passes over the pulley 24 and is attached to a drum 25 which is loosely mounted on the shaft. At one end of the 85 drum are spur teeth 26. A pawl 27 is provided for engaging the spur teeth and locking the drum against rotation when desired. The pawl is pivotally mounted as at 28 and has an arm 27. A spring 30 for engaging 90 the pawl with spur teeth of the drum is attached to said arm. A lever 31 is provided for tripping the pawl and is connected by a link rod 32 to the pawl arm 29. A segment 35 and dog 34 are provided to lock the lever 95 31 in adjusted position.

I also provide a clutch 25 which is here shown as a friction clutch for locking the drum to the shaft, for rotation with the shaft when desired, to cause the drum to 100 wind up the rope and thereby pull up the tool from the well. When the clutch is disengaged from the drum, and the pawl is engaged with the drum, the latter is held stationary so that the rope will suspend the 105 tool at the required point in the well and permit the trip lever, which is operated by the tappet pins, to impart the required vertical reciprocating motion to the tool and hence cause the latter to drill the well. This 110 clutch is provided with a shipper lever 36 to enable the clutch to be operated and the

shipper lever may be held in adjusted position by a dog 37 which may be engaged with either of a pair of lock notches 38, 39.

By adjusting the cam by means of its lever 16, the length of the stroke of the tappet lever, and hence also of the tool, may be adjusted as desired.

It will be observed that the controlling levers are all arranged at one end of the machine and in close proximity to one another so that only one operative is required. He is stationed at said end of the machine and may grasp and operate either of said levers to regulate the length of the stroke of the tool and to wind or pay out the rope by the drum, as may be required from time to time during the operation of the machine. As the spur wheel is provided with two of the tappet pins which are arranged diametrically opposite each other, and as the tappet pins successively impart tool lifting stroke to the trip lever, the latter causes the tool to deliver two strokes to each rotation of the shaft so that the well drilling proceeds very expeditiously.

Having described the invention, what is claimed is:

1. In a well drilling machine of the class described, a frame, a shaft mounted in bearings in the frame, means to rotate the shaft, an element revoluble with the shaft, a tappet pin mounted for reciprocating movement in said element and arranged substantially parallel with the shaft, a trip lever pivotally mounted on said shaft to operate a drill rope and arranged in the path of said tappet pin, a relatively fixed cam to operate the said tappet pin and cause the same to engage and disengage said trip lever at each rotation of the shaft, a drum mounted loosely on the shaft for winding and unwinding the drill rope, means to lock and release the drum, and means to lock the drum to or release the same from the shaft.

2. In a well drilling machine of the class described, a frame, a shaft mounted in bearings in the frame, means to rotate the shaft, an element revoluble with the shaft, a tappet pin mounted for reciprocating movement in said element and arranged substantially parallel with the shaft, a trip lever pivotally mounted on said shaft to operate a drill rope and arranged in the path of said tappet

pin, a cam to operate said tappet pin and cause the same to engage and disengage the said trip lever at each rotation of the shaft, said cam being loosely mounted on said shaft, means to adjust said cam to regulate the length of stroke of the trip lever, a drum mounted loosely on the shaft for winding and unwinding the drill rope, means to lock and release the drum, and means to lock the drum to or release the same from the shaft.

3. In a well drilling machine of the class described, a frame, a shaft mounted in bearings in the frame, means to rotate the shaft, an element revoluble with the shaft, a tappet pin mounted for reciprocating movement in said element and arranged substantially parallel with the shaft, a trip lever pivotally mounted on said shaft to operate a drill rope and arranged in the path of said tappet pin, a relatively fixed cam to operate said tappet pin and cause the same to engage or disengage said trip lever at each rotation of the shaft, a drum mounted loosely on the shaft for winding and unwinding the drill rope and provided with ratchet teeth, a pawl to engage and disengage the ratchet teeth and thereby lock or release the drum, and means to lock the drum to or release the same from the shaft.

4. In a well drilling machine of the class described, a frame, a shaft mounted in bearings in the frame, means to rotate the shaft, an element revoluble with the shaft, a tappet pin mounted for reciprocating movement in said element and arranged substantially parallel with the shaft, a trip lever pivotally mounted on said shaft to operate a drill rope and arranged in the path of said tappet pin, a relatively fixed cam to operate the said tappet pin and cause the same to engage and disengage said trip lever at each rotation of the shaft, a drum mounted loosely on the shaft for winding and unwinding the drill rope, means to lock and release the drum, and a clutch to lock the drum to or release the same from the shaft.

In testimony whereof I affix my signature in presence of two witnesses.

JOHN A. SHANLEY.
